TAPE HOLDER AND DISPENSER

Clarence W. Vogt, Weston, Conn.

Application July 15, 1954, Serial No. 443,630

16 Claims. (Cl. 164—84.5)

This invention relates to devices for holding and dispensing adhesive tapes such, for example, as "cellophane" type tapes, fiber reinforced tapes, woven tapes and tapes coated with pressure sensitive and other forms of adhesives, and more particularly to devices of the above character which may be operably positioned upon a surface such as a desk or table for dispensing such tapes in suitable lengths.

In applicant's copending application Serial No. 428,884, filed May 11, 1954, there is described a tape dispenser suitable for use upon a desk or table from which tape may be dispensed and severed as desired. Means are described in the previously filed application for suitably snubbing and cutting the tape material being dispensed from the holder, and these functions are performed by mechanism in the present device in a somewhat similar manner but with certain essential differences therebetween. Accordingly, it is an object of the present invention to provide an improved desk type tape dispenser which may be inexpensively manufactured and assembled.

It is another object of the invention to provide a tape dispenser of the above character in which the various elements may be easily disassembled to facilitate rapid loading of the device.

It is still another object of the invention to provide a tape dispenser of the above character in which the cutting blade cooperates with deformed mounting pin means for urging the tape against a surface serving to rigidly position the free end of the tape.

These and further objects of the invention are accomplished by providing a base having a recess therein, the base preferably being molded in a unitary piece from an inexpensive material such as glass. Bosses having a suitable configuration are vertically disposed in the recesses and cooperate with a further unit carrying a snubbing and cutting blade to secure such unit in the base. The unit also carries hub means mounting a roll of the tape to be dispensed and is preferably molded in a unitary piece from a suitable plastic material. The unit includes elements cooperating with the blade to add a slight curvature longitudinally of the tape at its free end, such curvature imparting rigidity to the free end to aid in maintaining it in a predetermined position.

These and further objects and advantages of the invention will be more readily understood when the following description is read in connection with the accompanying drawings in which:

Figure 1 is a side elevation illustrating the tape holding, severing and positioning mechanism;

Figure 2 is a longitudinal section of the mechanism of Figure 1 taken on the view line 2—2 looking in the direction of the arrows;

Figure 3 is a partial view in front elevation, somewhat enlarged, of the unit mounting the cutting blade and tape illustrated in Figure 1;

Figure 4 is a partial view in plan, somewhat enlarged, of the unit illustrated in Figure 1;

2

Figure 5 is a partial longitudinal section, somewhat enlarged, taken on a plane intermediate the sides of the unit shown in Figure 1;

Figure 6 is a partial longitudinal section similar to Figure 5 illustrating the mechanism in the unit in another operative position;

Figure 7 is a plan view of a snubbing and cutting blade, somewhat enlarged, for use in the unit illustrated in Figure 1;

Figure 8 is a longitudinal section of a desk tape holder and dispenser, but showing the unit of Figure 1 in side elevation, taken on the view line 8—8 of Figure 10 looking in the direction of the arrows;

Figure 9 is a plan view of the desk tape dispenser illustrated in Figure 8 with the tape holding, severing and positioning unit omitted;

Figure 10 is a transverse section of the tape holder shown in Figure 8 taken on the view line 10—10 looking in the direction of the arrows;

Figure 11 is another transverse section of the tape holder taken on the view line 11—11 of Figure 9 looking in the direction of the arrows; and

Figure 12 is a side elevation of a cover, shown in position in Figure 8, that may be employed with the desk type tape holder.

Referring to an illustrative embodiment of the invention in greater detail with particular reference to the drawings, side plates 10 and 11 are mounted on opposite sides of a bridge 12 carrying a protruding stop 13. Lugs 10a, 10b and 11a, 11b are respectively formed on the extremities of the lower edges of the plates 10 and 11. Also joining the side plates 10 and 11 is a blade mounting pin 14 deformed by a rib 15 extending longitudinally thereof.

Flanges 16 and 17 extend inwardly from the forward upper portions of the side plates 10 and 11, respectively. Formed on the flanges 16 and 17 are triangularly shaped surfaces 18 and 19 sloping obliquely from the interior towards the plates 10 and 11, respectively. Flat lower snubbing surfaces 20 and 21 are found under the flanges 16 and 17, respectively, these surfaces being shaped and positioned to cooperate with a snubbing and cutting blade indicated generally at 22.

The blade 22 is formed at the left hand extremity thereof, as shown in Figure 7, with a cutting edge 23 and at the right hand extremity with a snubbing surface 24 formed by rolling a portion thereof. A short distance to the rear of the cutting edge 23 on the blade 22 are found a pair of surfaces 25 and 26 angularly positioned to cooperate with the surfaces 18 and 19, respectively. As may be clearly seen from Figures 5 and 6, the blade is formed with a curved channel 27, this construction permitting the blade 22 to be snapped on the pin 14. Reverse bends 28 and 29 in the form of loops are also formed adjacent to the channel 27 to add resilience to the blade 22.

A tape 30, coated on its upper surface, is passed from a roll 31 under the snubbing surfaces 20 and 21 and selectively extends upwardly against the positioning surfaces 18 and 19 (Figure 5) or outwardly in contact with the blade 22 (Figure 6).

The blade 22 is formed in such a fashion that the snubbing surface 24 is adapted to engage and press the adhesive coated tape 30 against the snubbing surfaces 20 and 21 in order to snub the tape 30 and prevent it from being withdrawn from the roll 31 while it is being severed, as illustrated in Figure 6.

Initially the tape 30 is in the position shown in Figure 5 with its free end 32 extending upwardly and with the blade surfaces 25 and 26 urging it against the surfaces 18 and 19. The tape 30 may be affixed to any suitable

article and subsequently, a predetermined length thereof longitudinally pulled from the holder. To sever the tape 30, it is pressed downwardly against the cutting edge 23 which causes the snubbing surface 24 to press it against the surfaces 20 and 21. Further downward pressure on the tape 30 flexes the blade 22 until it reaches the stop 13, the resilient loops 28 and 29 permitting a substantial movement thereof. Further downward pressure cuts the tape 30 on the cutting edge 23.

Immediately after the tape 30 has been severed, the blade 22 will be released and spring upwardly about the pin 14. As the surfaces 25 and 26 approach the surfaces 18 and 19, the rib 15 on the pin 14 will tend to spread the channel 27 due to its configuration (Figure 5). Thus, the inner wall of the channel 27 will be in tension on the shaft 14 and the rib 15 and the blade 22 will be held in place against the surfaces 18 and 19. As mentioned above, these surfaces are oriented to impart to the free end 32 of the tape 30 a curved configuration to hold it rigidly in position.

A number of advantages are obtained by using a snap-on type blade 22 in the tape holder and dispenser. The particular type, composition and gauge of the tape used determines the characteristics of the blade 22. Thus, the sharpness of the pointed edge 23 and the resilience and hardness of the blade must be considered in choosing a blade for particular tapes to make certain the tape will be cleanly severed and the blade returned to the position shown in Figure 5. With certain stretchable tapes such, for example, as one of the new polyesters known as "Mylar," it may be advantageous to provide a protuberance on the point of the edge 23 as shown in applicant's copending application Serial No. 396,144, filed December 4, 1953, now Patent No. 2,805,714, issued September 10, 1957. With the employment of the snap-on type blade, the blade best suited to a particular tape being used may be easily and quickly snapped into place on the cutting unit.

Respectively formed on the upper edges of the side plates 10 and 11 rearwardly of the flanges 16 and 17 are a pair of ears 33 and 34 serving to prevent the free end 32 from being folded back and contacting the lead of the tape 30 between the roll 31 and the flanges 16 and 17. These ears also function to secure a cover on the tape holder and dispenser as will be described hereinafter.

Formed on the upper portion of the side plates 10 and 11 is a hub indicated generally at 35 for supporting the roll of tape 31. The hub 35 is formed from a pair of circular pieces 36 and 37 extending obliquely rearwardly from inwardly extending flanges 38 and 39, preferably formed integrally with the rear edges of the side plates 10 and 11, respectively. The pieces 36 and 37 abut each other at their rear extremities and have formed thereon outwardly and rearwardly extending keying lugs 40 and 41, respectively. As may be clearly understood by referring to Figure 2, to mount the roll 31 on the hub 35 it is merely necessary to insert a finger on one hand in the gap between the pieces 36 and 37 to flex the side plates 10 and 11 outwardly and subsequently to insert the roll in the thus widened gap with the other hand.

After mounting the roll of tape 31 on the hub 35, the free end 32 of the tape may be withdrawn and then twisted or folded to permit it to be passed between the flanges 16 and 17. Thus, due to the spaced positioning of the flanges 16 and 17, the tape loading operation is considerably simplified since it need not be threaded into position.

Referring next to the desk tape holder and dispenser as an operative unit with particular reference to Figures 8 to 12, inclusive, a base 42 having a longitudinally extending recess 43 is preferably molded as a unitary piece from a material such as glass, for example. The recess 43 is formed with an arcuate configuration in the rear of the base and extends forwardly and upwardly from a discontinuity in the floor thereof at the point 44. Upwardly

extending circularly shaped portions 45 and 46 may be formed on the upper surface of the base 42 on both sides of the recess 43.

Disposed on both interior vertical walls of the recess 43 and extending to the portions 45 and 46 are a pair of locking bosses 47 and 48 shaped to secure the remaining elements of the dispenser in operative position as will be apparent from the following discussion. Forward edges 49 and 50 of the bosses 47 and 48, respectively, extend in a straight line slanted rearwardly from the floor of the recess 43 to the portions 45 and 46, respectively. In addition, rear edges 51 and 52 of the bosses 47 and 48, respectively, each contain a substantially vertical lower edge and a rearwardly slanting upper edge, the upper edges preferably being substantially parallel to the forward edges 49 and 50.

Formed on the floor of the upwardly extending forward portion of the recess 43 is a spreader lug 53 protruding upwardly and having its sides 54 and 55 bowed outwardly (Figures 9 and 11).

A rubber pad 62 on the bottom of the base 42 serves to protect the finish of the surface supporting the tape holder and dispenser.

In assembling the desk type tape holder and dispenser, the holding and serving unit including the roll of tape 31 is inserted into the recess 43 with the rear straight edges of the side plates 10 and 11 contacting the edges 49 and 50 of the bosses 47 and 48, respectively, and the lugs 10a and 11a abutting the point 44. It will be noted that the lugs 10b and 11b will hang over the forward lip of the recess 43. The forward edges of the keying lugs 40 and 41 will at the same time engage the upper edges of the rear edges 51 and 52 of the bosses 47 and 48. In addition, the spreader lug 53 will engage the interior surfaces of the side plates 10 and 11 and bow them outwardly by virtue of the surfaces 54 and 55 to provide a positive frictional holding force therebetween.

In pulling the tape 30 from the roll 31, the longitudinal force exerted will be carried by the bosses 47 and 48 through the keying lugs 40 and 41. On the other hand, urging the tape 30 downwardly against the cutter blade 22 forces the rear edges of the plates 10 and 11 against the front edges 49 and 50 of the bosses 47 and 48. In addition, in the event the entire holder is turned upside down, the spreader lug 53 will function to retain the tape cutting, holding and positioning unit in its operative position in the base 42.

If desired, a cover 56 may be provided to enclose the roll of tape 31. Formed on the cover 56 is a bead 57 adapted to engage the base 42 as will be explained hereinafter. Centering tongues 58 and 59 extend from the lower side of the cover 56 while a flange 60 is formed on the forward edge thereof. A small protrusion 61 is centered on the cover 56 slightly to the rear of the flange 60.

In assembling the cover with the remaining elements of the tape holder, the flange 60 is snapped under the ears 33 and 34 and the centering tongues 58 and 59 are inserted between the rear edges of the plates 10 and 11 and the forward edges of the keying lugs 40 and 41. It will be apparent from Figures 8 and 10 that the bead 57 will then engage the upper surface of the base 42 including the edges of the portions 45 and 46. The protrusion 61 functions to prevent the free end 32 of the tape 30 from adhering to the flat upper surface of the cover 56 thus making it simple to remove it therefrom after the device has been removed from its package, for example.

It will be understood that the above described embodiments of the invention are illustrative only and modifications thereof will occur to those skilled in the art. Therefore, the invention is not to be limited to the specific apparatus disclosed herein but is to be defined by the appended claims.

I claim:

1. In an adhesive tape dispenser, at least one side plate, means adjacent to the side plate to support a roll of the

adhesive tape, deformed pin means supported by the side plate, a resilient snubbing and cutting blade formed with a channel for pivotal mounting on the pin means, tape positioning means supported by the side plate and adapted to be engaged by the free end of the tape extending from the roll, the deformed pin means having a first surface portion at a different radial distance from the pin axis than a second surface portion, the surface portions engaging and deforming the channel to hold a portion of the blade against the free end of the tape on the tape positioning means, the tape free end when grasped for dispensing tape urging the blade away from the tape positioning means and causing the blade to pivot on the deformed pin means.

2. Apparatus as defined in claim 1 wherein the blade is formed with a cutting edge at one end and a snubbing surface at the other end and the channel is nearer the snubbing end than the cutting end.

3. In an adhesive tape dispenser, a holding and severing unit comprising two spaced side plates, means adjacent to the side plates to support a roll of the adhesive tape, deformed pin means supported by the side plates, a resilient snubbing and cutting blade formed with a channel for pivotal mounting on the pin means, tape positioning means supported by the side plates and adapted to be engaged by the free end of the tape at an angle to the lead of the tape extending between the roll and the positioning means, the deformed pin means including a protrusion engaging and deforming the channel to hold a portion of the blade against the free end of the tape on the tape positioning means, the tape free end when grasped for dispensing tape urging the blade away from the tape positioning means and causing the blade to pivot on the deformed pin means.

4. Apparatus as defined in claim 3 wherein the protrusion comprises a rib extending longitudinally on the pin, said rib engaging and deforming the channel to hold a portion of the blade against the free end on the tape positioning means.

5. In an adhesive tape dispenser, a holding and severing unit comprising two spaced side plates, hub means formed on the rear of the side plates adapted to mount a roll of the adhesive tape, tape positioning means supported by the plates and adapted to be engaged by the free end of the adhesive tape extending from the roll, deformed pin means supported by the side plates, a resilient snubbing and cutting blade formed with a channel for pivotal mounting on the pin means, the deformed pin means including a protrusion engaging and deforming the channel to hold a portion of the blade against the free end of the tape on the tape positioning means, the tape free end when grasped for dispensing tape urging the blade away from the tape positioning means and causing the blade to pivot on the deformed pin means and a snubbing surface formed on the tape positioning means against which the free end of the tape is pressed by the blade.

6. Apparatus as defined in claim 5 wherein the hub means comprises a pair of circular pieces supported by the rear edges of the side plates, respectively, each of the pieces carrying a guide lug on its extremity.

7. Apparatus as defined in claim 6 wherein the circular pieces are angularly oriented to engage at their extremities and the roll of tape carried thereby is partially disposed between the side plates.

8. In an adhesive tape dispenser, a holding and severing unit comprising two spaced side plates, means for supporting a roll of the tape at the rear of the plates, tape positioning means supported by the plates and adapted to be engaged by the free end of the adhesive tape at an angle to the lead of the tape extending between the roll and the positioning means, deformed pin means supported by the side plates, a resilient snubbing and cutting blade formed with a channel for pivotal mounting on the pin means, the deformed pin means including a protrusion engaging and deforming the channel to hold a portion of

the blade against the free end of the tape on the tape positioning means, the tape free end when grasped for dispensing tape urging the blade away from the tape positioning means and causing the blade to pivot on the deformed pin means, a snubbing surface formed on the tape positioning means against which the free end of the tape is pressed by the blade, and transversely extending guard means supported by the plates rearwardly of the tape positioning means for preventing the free end from engaging the lead of the tape.

9. Apparatus as defined in claim 8 wherein said guard means comprises an ear supported on the upper edge of each of the side plates.

10. In an adhesive tape dispenser, a holding and severing unit comprising two spaced side plates, hub means formed on the rear of the side plates adapted to mount a roll of the adhesive tape, tape positioning means supported by the plates and adapted to be engaged by the free end of the adhesive tape at an angle to the lead of the tape extending between the roll and the positioning means, guard means supported by the plates rearwardly of the tape positioning means, deformed pin means supported by the side plates, a resilient snubbing and cutting blade formed with a channel for pivotal mounting on the deformed pin means, and a snubbing surface on the tape positioning means against which the free end of the tape is pressed by the blade when the tape is urged against the resilient blade for tensioning said blade and severing the tape free end, the blade moving the free end of the tape against the tape positioning means after the tape has been severed, the deformed pin means including a protrusion engaging and deforming the channel to hold a portion of the blade against the tape positioning means, the tape free end when grasped for dispensing tape urging the blade away from the tape positioning means and causing the blade to pivot on the deformed pin means.

11. A tape holder and dispenser comprising a tape holding and severing unit including a pair of side plates, hub means disposed on the rear of the side plates adapted to mount a roll of the tape with the free end thereof extending between the side plates, tape positioning means supported by the plates and adapted to be engaged by the free end of the tape, a snubbing and cutting blade pivoted between the plates, a snubbing surface formed on the tape positioning means against which the free end of the tape is pressed by the blade, a pair of keying lugs provided on each side of the hub means, a base formed with a longitudinal recess, and locking means on each side of the recess cooperating with the rear of the side plates and the keying lugs to secure the unit in the recess against forces applied to the free end of the tape.

12. A tape holder and dispenser comprising a tape holding and severing unit including a pair of side plates each formed with a rear edge having a straight section, hub means supported by the upper rear portions of the side plates and adapted to mount a roll of the tape with the free end thereof extending between the side plates, tape positioning means supported by the plates and adapted to be engaged by the free end of the tape, a snubbing and cutting blade pivoted between the plates, a snubbing surface formed on the tape positioning means against which the free end of the tape is pressed by the blade, a pair of keying lugs each having a straight edge on its forward portion provided on each side of the hub means at its extremity, a base formed with a longitudinal recess, a boss extending upwardly from the floor of the recess on each side thereof and cooperating with the rear edges on the side plates and the straight edges on the keying lugs to secure the unit in the recess against forces applied to the free end of the tape.

13. Apparatus as defined in claim 12 wherein the rear edges on the side plates and the straight edges on the keying lugs are substantially parallel and the bosses are formed with a pair of substantially parallel edges cooperating with the rear and straight edges.

14. Apparatus as defined in claim 12 in which a lug extending upwardly from the floor of the recess engages and spreads the side plates to additionally secure the holding and severing unit in the recess.

15. Apparatus as defined in claim 12 in which one end of a cover is secured on the tape holding and severing unit and the other end is supported by the rear of the recess in the base.

16. An article of manufacture comprising a resilient tape snubbing and cutting blade formed with a cutting edge at one end thereof, a snubbing surface at the other end thereof, a transversely extending open channel for pivoting the blade formed therein nearer the snubbing end than the cutting edge, portions on the blade between the channel and the cutting edge having tape engaging surfaces lying at angles to each other, and a reverse bend

5

10

15

constituting a loop formed in the blade adjacent to at least one side of the channel for increasing the resilience of the blade.
